UNITED STATES PATENT OFFICE.

JOHN A. FISHER, OF SANDUSKY, OHIO.

AMUSEMENT DEVICE.

Application filed March 16, 1922. Serial No. 544,135.

To all whom it may concern:

Be it known that I, JOHN A. FISHER, a citizen of the United States, and residing in the city of Sandusky, in the county of Erie 5 and State of Ohio, have invented or discovered the new, useful, and Improved Amusement Device, of which the following is a specification.

My invention consists in certain new and 10 useful improvements in amusement devices of the general type wherein a passenger car is caused to travel along a track continuous or otherwise.

More particularly, my invention is characterized by the imparting to the cars of a motion in addition to its travel along the track. This additional motion is preferably, but not necessarily, a rotary motion about an axis either coincident with or parallel to the 20 axis of the car.

Such motion may be imparted to the car in any suitable manner. Thus, it may be voluntarily imparted by a passenger, but I prefer to automatically impart such motion 25 to the car by the travel of said car along the track.

Thus, in such preferred form the track is provided with undulations or changes of level disposed either longitudinally or transversely of the track, and the car is so mounted or arranged that it will automatically rotate or swing in response to the track variations.

Such automatic rotation may be produced 35 in a number of ways which will suggest themselves to those skilled in the art. For instance the axis upon which the car rotates may be so disposed or the seats or accommodations for the passengers may be so arranged, that the burden is disposed eccentrically to the axis of rotation, so that the heavy side or portion of the car will tend to swing to the lower side in response to variations in track level, and inclinations in opposite directions will cause the car to swing back and forth.

To prevent the car from spinning, I prefer to provide means for limiting the rotary movement of the car in either direction, and 50 I also provide means for cushioning such limitation to avoid jolting and jarring. Means are also provided for automatically returning the car to its normal position when

at rest or traveling along a horizontal portion of the track. 55

I also provide novel means whereby the passenger may resist, control or augment the automatic rotation of the car.

Other novel features of construction and arrangement of parts will appear from the 60 following description.

In the accompanying drawings which are however merely intended to illustrate a practical embodiment of the principles of my invention without limiting the scope 65 thereof to the construction shown, Fig. 1 is a diagrammatic view in the side elevation of a portion of the track of an amusement device provided with longitudinal undulations or dips and rises and also with lateral or transverse inclinations in opposite directions; Figs. 2, 3 and 4 are cross sectional views of the track supposed to be taken along the lines II-II; III-III, and IV-IV in Fig. 1; Fig. 5 is a side elevation of 70 the preferred form of passenger car shown rotatably mounted on a wheeled truck; Fig. 6 is a plan view of the same; Fig. 7 is a bottom plan view of the same showing the truck, and Fig. 8 is a side elevation of a 75 modified form of car.

The following is a detailed description of the drawings.

Referring first to Fig. 1, A and A' represent the two rails of the track, which track is shown in Fig. 1, with longitudinal undulations or dips and rises a, b and c and also lateral or transverse inclinations in either direction so that one rail is now higher and now lower than the other. 85 90

The cars B are rotatably mounted on the trucks C, and said trucks are provided with flanged wheels 1 which run on the rails A or A'. I prefer to use three wheeled trucks 95 as the same have not the same tendency to bind or jump on an uneven track as have four wheeled trucks.

The cars are caused to travel around the tracks by any convenient means. Thus, in Fig. 5 I have indicated a pulling cable 2. The cars may be connected to form trains, as by the coupler bars 3. 100

Any convenient method of rotatably mounting the car on the truck may be used. Thus, in Figs. 5, 6 and 7 I have shown a 105 pivot post 4 fixed to the platform 5 of the

truck and extending vertically up through the floor 6 of the car, the car thus rotating with the post as an axis. 7 represents an arc shaped bearing member fixed on the truck 5 platform 5 on which slides a similar member 8 carried by the car floor, thereby steadyng the rotation of the car.

To limit the rotation of the car, and thereby prevent spinning, I provide a pair of 10 stops 9 on the truck platform which are adapted to be engaged by the ends of the bearing member 8.

To prevent jolting and jarring by violent engagément of bearing member 8 with the 15 stops 9, I provide cushion means comprising a pair of helical springs 10 attached to the truck platform and diverging to be attached to the car at points spaced apart. Said springs also perform the function of automatically returning the car to its normal 20 position when at rest or traveling along a level portion of the track.

The upper end of the pivot post 4 is provided with a fixed hand wheel 11 which 25 I term the "steering wheel."

12 represents the passenger seat, or seats, which are omitted at one side of the car where a doorway 13 is provided.

It is thus evident that the burden of the 30 loaded car is eccentric to its axis, and therefore as the truck travels along the rails, the changes of level in the track will cause the car to rotate on its axis, the heavier or loaded portion of the car tending to swing 35 to the low side. For instance, as the truck ascends a rise, the heavy side of the car would swing around to the rear, and as the truck descends a dip the heavy side of the car will swing around to the front. Likewise, 40 in the case of lateral or transverse inclinations in the track, the heavy side of the car will swing to the lower side.

The result is that the car will swing back and forth. A passenger, by grasping the 45 steering wheel 11 and exerting his weight or strength may resist and more or less overcome the tendency of the car to rotate, or he may augment such tendency, or on level portions of track the passenger may cause 50 the car to rotate on its pivot.

In Fig. 8 I have shown the post 4 fixed to the floor of the car instead of the car being pivoted on said post. In this case the pivotal connection is effected by the trunnion member 14 depending from the floor of the car and journaled in a vertically disposed bearing 55 15 in the truck platform 5.

In the drawings I have shown the track characterized by both longitudinally and 60 transversely disposed variations in level or undulations, but it will be understood that either character of variations alone will produce the desired rotation. It is also evident that the track may be straightaway, sinuous, 65 curved, oval or annular.

It is evident from the foregoing that my invention adds greatly to the novelty and attractiveness of amusement devices of this general type.

Although, for the sake of clearness, I have 70 described in detail the embodiment of the principles of my invention shown in the drawings, I do not wish to limit myself thereby, but claim broadly:—

1. In an amusement device, the combination 75 of a support traveling along a path characterized by variations of level, a passenger car rotatably mounted on said support, means whereby the travel of said support along said path causes said car to rotate on said support, and resilient means resisting said rotation.

2. In an amusement device, the combination 80 of a support traveling along a path characterized by variations of level, a passenger car rotatably mounted on said support, means whereby the travel of said support along said path causes said car to rotate on said support, means for limiting said rotation, and means for cushioning said limitation.

3. In an amusement device the combination 85 of a support traveling along a path characterized by variations in level, and a passenger car rotatively mounted on said support, said car being mounted in such a manner that when loaded it is eccentric to its axis of rotation whereby the travel of said support causes said car to rotate on said axis.

4. In an amusement device, the combination 90 of a support traveling along a path characterized by variations of level, a passenger car rotatively mounted on said support, said car being mounted in such a manner that when loaded it is eccentric to its axis of rotation whereby the travel of said support causes said car to rotate on said axis, and means for limiting the rotation 95 of said car.

5. In an amusement device, the combination 100 of a support traveling along a path characterized by variations of level, a passenger car rotatively mounted on said support, said car being mounted in such a manner that when loaded it is eccentric to its axis of rotation whereby the travel of said support causes said car to rotate on said axis, and cushioned means for limiting the 105 rotation of said car.

6. In an amusement device, the combination 110 of a track, a passenger car adapted to travel along said track, means whereby the car is caused to rotate on its axis while traveling along the track, and means whereby the occupant of the car may augment and retard such rotation.

7. In an amusement device, the combination 115 of a track, a passenger car adapted to travel along the track, means whereby the 120

travel of the car along the track tends to impart an additional movement of the car, and means whereby said additional movement may be controlled by an occupant of 5 the car.

8. In an amusement device, the combination of a traveling support, a passenger car rotatably mounted on said support, and a steering device mounted on said support and 10 operatable by an occupant of the car for regulating the rotary movement of said car relative to said support.

9. In an amusement device, the combination of a traveling support, a vertically disposed steering member fixedly mounted on 15 said support, and a passenger car mounted on said support and rotatable thereon with said steering member as an axis.

10. In an amusement device, the combination of a traveling support, a passenger car rotatably mounted on said support, and a member rigidly mounted on said support and adapted to be grasped by an occupant 20 of said car to swing said car on its axis 25 relative to said support.

11. In an amusement device, the combination of a track, a passenger car adapted to travel along said track, means whereby said car is caused to rotate on its axis by its travel along said track, and independent 30 means operatable by an occupant of the car whereby the latter may cause the car to rotate on its axis.

12. In an amusement device, the combination of a track, a support adapted to travel 35 along said track, a car rotatably mounted on said support, and means operatable by an occupant of the car whereby the latter may be caused to rotate on said support.

13. In an amusement device, the combination of a traveling support, a vertically disposed post fixed on said support, a car rotatably mounted on said support as an axis, and means carried by said post and adapted 40 to be grasped by an occupant of said car 45 whereby the car may be rotated relative to the support.

Signed at Sandusky, Ohio, this 10th day of March, 1922.

JOHN A. FISHER.
